UNITED STATES PATENT OFFICE.

WILLIAM S. HASLEU, OF MONTEVIDEO, MINNESOTA.

STOKER.

1,206,701.

Specification of Letters Patent. Patented Nov. 28, 1916.

Application filed February 9, 1915. Serial No. 7,184.

To all whom it may concern:

Be it known that I, WILLIAM S. HASLEU, a citizen of the United States, residing at Montevideo, in the county of Chippewa and State of Minnesota, have invented new and useful Improvements in Stokers, of which the following is a specification.

The present invention relates to improvements in mechanical stokers which, while primarily adapted for use upon locomotives or in connection with locomotive boilers, it is to be understood is applicable to stationary boilers and all other devices of like nature where it is desired to feed the fuel automatically.

In carrying out my invention I aim to provide an efficient and economical yet reliable means for mechanical stoking which will economize space and which can be readily disconnected, removed or set aside to permit of the ordinary hand firing when occasion requires.

It is also my object to provide a reliable and efficient device of this nature having provision for the distribution of the fuel as circumstances may require, as for instance, when it becomes desirable to feed only to one side, again to the other side, and still again to the center of the fire box as well as to direct the supply of fuel nearer or farther from the rear end of the fire box.

It is a further object of the invention to construct a stoker which shall include a rotary feeder provided with means for directing the coal from the feeder to the fire box and to regulate the speed of the feeder so that coal of various sizes and quantity may be properly projected into the fire box and the force of the projecting readily ascertained by a suitable gage so that the distance the coal is thrown in the fire box is known to the operator or engineer and may be changed by regulating a governor associated with the propelling mechanism.

It is a further object of the invention to provide for the ready inspection of the fire at any time, as well as for the introduction of a poker or hook for leveling the fuel and to permit of the shaking of the grates by merely moving the device to either side of the engine cab.

It is a still further object of the invention to construct a stoker which includes a rotary feed member arranged upon a track in the cab of an engine and movable to either side thereof when not employed for direct-

ing fuel into the fire box, to arrange suitable means for actuating the rotor blades of the feeder, to provide the device with a chute having a pivotal support so as not to interfere with the movement of the feeder and to employ the mechanism for actuating the rotor of the feeder for imparting movement to the chain flights of the chute, and further to associate with the chute a longitudinally as well as a laterally movable elevator or conveyer which has associated therewith a rotary shovel and which delivers to the chute and which is actuated by the same power which operates the chute and feeder, and I aim also to improve the details of the construction whereby the desired end is attained in an efficient and satisfactory manner and to reduce the cost of the installation and operation of the apparatus.

With the above and other objects in view, the improvement resides in the construction, combination and arrangement of parts set forth in the following specification and falling within the scope of the appended claims.

The essential features of the invention involved in carrying out the objects above indicated are necessarily susceptible of embodiment in various forms of construction without departing from the scope of the invention, but certain preferred and practical embodiments are exemplified in the accompanying drawings, in which:

Figure 1 is a side elevation of the improvement showing the application thereof, 90 adjacent portions of a locomotive and tender upon which the improvement is arranged being shown in section, Fig. 2 is a top plan view of the device as illustrated in Fig. 1, the cab of the locomotive being shown in section, Fig. 3 is a detail enlarged central vertical longitudinal sectional view approximately on the line 3—3 of Fig. 2, Fig. 4 is a plan view, partly in section, the conveyer for the rotary bucket being removed, 100 Fig. 5 is a detail enlarged elevation illustrating the connection of the conveyer with the chute and also illustrating the mechanism for moving the conveyer longitudinally of the chute, Fig. 6 is a sectional view on the line 6—6 of Fig. 5, and also looking in the direction of the arrows, Fig. 7 is a perspective view of the rotary feeder, Fig. 8 is a face view of the same, Fig. 9 is a detail side elevation of one end of the elevator 105 showing the arrangement of the supporting carriage and the rotary shovel thereon and

looking in the direction of the delivery face of the shovel, Fig. 10 is a sectional view on the line 10—10 of Fig. 9, Fig. 11 is a vertical transverse sectional view taken approximately in a line with the shaft of the rotary shovel, and Fig. 12 is a view of the indicator and its connection with the power shaft.

Like numerals of reference indicate corresponding parts throughout the several views.

In the drawings 1 designates a tender, 2 the deck thereof, 3 the fire box of the boiler 4, 5 the engine deck and 6 the ordinary apron bridging the space between the adjacent decks 2 and 5.

The above mentioned elements may be of any of the well known types and equipped in the ordinary manner, there being nothing claimed as new about these parts except in the particulars to which attention will be drawn.

Arranged within the coal bin of the tender 1 is a rotary shovel 7, the same having its shaft 8 journaled in suitable bearings provided in the side members of a wheeled truck or carriage 9, the wheels of the said truck being in the nature of pivoted casters 10, so that the carriage as well as the rotary shovel may be moved longitudinally or laterally of the bin as occasion requires, and for a purpose which will hereinafter be more fully understood. The shovel, as shown in the drawings, includes two spaced disks 7^a and 7^b which are centrally connected by a sleeve 8^a which receives and has secured therein the shaft 8. The disk 7^a is of a greater diameter than the disk 7^b, and upon the periphery of these disks is secured a rim 11. This rim forms one of the walls of a plurality of radially disposed buckets 12. What I will term the rear walls of the buckets each comprise a plate 12^a and secured to and radiating from the rim 11 are outer side walls 12^b arranged in a line with the upper edge of the rim 11, inner side walls 12^c arranged parallel and substantially of a similar size to that of the side walls 12^b and outer members or plates 13 connecting the side walls 12^b and 12^c and the end plate 12^a thus providing each of the buckets with an open face and also with an opening between the inner edges of the walls 12^c and the inner periphery of the inclined rim 11. By this arrangement it will be noted that the coal can be received through the open mouth or face of the buckets and be delivered therefrom through the space or gap between the inner edges of the sides 12^c and the inner periphery of the inclined rim 11.

The numeral 14 designates a substantially U-shaped trough which is connected with the carriage 9, and disposed to the delivery side of the rotary shovel 7. The trough has

its side members provided with depending portions forming journals for the extending end of the shaft 8, and the said shaft between the journals has fixed thereon a sprocket wheel 15. The opposite end of the trough is also provided with a substantially U-shaped bracket 22 which has its arms provided with alining openings forming bearings of the shaft 17' for a second sprocket wheel 16, while traveling over the said sprocket wheels 15 and 16 is an endless chain 17, the same being provided with flights 18 which travel within the U-shaped trough and which are arranged transverse thereof so that the fuel when delivered from the shovel to the endless conveyer within the trough will be deposited from the outer or free end of the said trough.

The shaft 17' has one of its ends projecting beyond its bearing and is provided with a beveled tooth wheel 19 that is adapted to mesh with a similar toothed wheel 20 which has its shaft journaled in a bearing support 21 formed integrally with the bracket 22 and extending vertically of the said bracket (see Fig. 6).

Arranged within the cab or engine of the locomotive preferably above its deck 5 and directly to the rear of the fire box 3 is a transverse track 27, the said track being of course disposed below the doorway 28 of the fire box 3. This track is adapted to receive the slotted or bifurcated ends 29 of downwardly extending arms 30, the said arms being provided upon longitudinally extending supports 31—31. The horizontal members of the angular supports are preferably arranged in a plane with or slightly above the lower wall provided by the fire box opening 28 and arranged upon the said supports is the casing 32 of a rotary feeder. The supports project beyond the casing 32 and are provided with a connecting member 33, while pivoted, as at 34, with the said connecting member 33 is a central arm 35' of a bifurcated or yoke member 36. The side members of the yoke 36 are arranged at an angle with respect to the central member 35' and the said arms project normally toward the fire box 3 and over the top of the casing 32 terminating approximately centrally of the said casing. The side arms of the said yoke are provided with registering openings which form bearings for a shaft 37, the said shaft projecting beyond the arms of the yoke and being further journaled in bearings 38 provided in the longitudinally extending side boards 39—39 of the frame or U-shaped trough of a delivery chute 40. Secured upon the shaft 37, between the bearings 38 is a sprocket wheel 41, and a second transverse shaft 42 is journaled in bearings in the opposite ends of the side bars of the trough, the said shaft 42 being likewise provided with a sprocket wheel 43, and each

of the sprockets 41 and 43 is adapted to receive an endless chain 44. The chain is provided with transverse flights 46 which travel between the side bars 39 of the substantially U-shaped trough for the conveyer 40. The side bars 39 of the trough are provided at their ends upon which the shaft 42 is journaled with downwardly extending members providing the sides of a vertically disposed standard 47, and this standard is formed with an enlarged flat circular head 48 which rests upon a flat circular bearing plate 49 secured to the deck 2 of the tender 1. The head is centrally formed with a reduced round extension 50 which passes through a round opening in the bearing plate 49, the end of said extension being threaded to receive a nut 51 or other securing means whereby the standard 50 may be removed when desired. The shaft 42 has one of its ends projecting through its bearing and is provided with a beveled toothed wheel 52, the same meshing with a similar toothed wheel 55 arranged upon a longitudinally extending shaft 54 which is parallel with one of the side boards 39 of the trough of the delivery chute, and the said shaft is journaled in suitable bearings carried by the said side board of the trough. Arranged longitudinally and in spaced relation with the other side board of the chute is a guide rod 56, the said guide rod being secured to the said board by suitable brackets or supports 57, and mounted for movement on the guide rod 56 is a sleeve 58. The sleeve is formed on one of the arms of a substantially U-shaped member or yoke 59, which is arranged transversely over the chute 40 and the second arm indicated by the numeral 60 is formed or provided with a transversely U-shaped terminal. The members 61—61 provided by the said terminal having openings through which pass the shaft 54, whereby the member 59 is afforded a support both by the guide rod 56 and the said shaft 54. The arm 60 is hollow and receives the extension of the shaft 26 of the beveled tooth wheel 20, and the said shaft 26 has its end between the arms or members 61 provided with a second beveled gear wheel 62, while meshing with the said beveled wheel 62 is a similar gear wheel 62' which is also arranged between the arms 61 and which is provided with a spline that is arranged in the longitudinally extending groove in the shaft 54. It will be noted that the shaft 26 provides a pivotal connection between the bracket member 22 and the yoke or bracket member 59. By an arrangement as above described it will be noted that when the shaft 54 is revolved, in a manner which will presently be described when the endless chain 44 of the delivery chute is set in motion (the travel of said chain being in the direction of the ro-

etary feeder), the same will simultaneously operate the elevator conveyer (the direction of travel being toward the chute) to deliver to the chute, while likewise the rotary shovel will be operated gathering and delivering the coal from the bin of the tender in the manner previously set forth. It will be further noted that the shaft 26, which as stated, provides a pivotal connection between the elevator and the delivery chute so that the conveyor may be swung in any desired direction in the bin of the tender and furthermore the elevator may be moved longitudinally to bring its shovel end toward or away from the delivery chute, the yoke 59 having its side arms movable upon both the guide rod 56 and the shaft 54, while still again the delivery chute may be swung laterally upon its pivotal standard 47, when the supports 31 are moved laterally upon the track 27 and so carrying therewith the rotary feeder 22. The importance of such an arrangement should be duly noted, first, because the elevator and its shovel may be readily moved to any part of the bin or tender to gather coal therefrom and deliver the same to the delivery chute regardless of the angle at which the said elevator or conveyor is caused to assume; second, the arrangement permits of the rotary feeder being moved to either side of the doorway of the fire box so that access may be obtained to the said fire box for raking the fire, dumping the grate, etc.; third, because the apparatus may be conveniently adjusted to occupy only a small space and not interfere with the movements of the engineer of the locomotive; and fourth, the elevator or conveyor may be moved to bring one of its ends over the rotary feeder to permit of the feeder, the delivery chute and the elevator conveyor being removed as a unit, while still again, the arrangement permits of the separate removal of either the elevator, the chute or the rotary feeder. The casing 32 is provided with a frusto-conical top having a central opening 63 to receive the fuel from the delivery chute, and the fuel feeder 64 preferably comprises a plurality of straight plates 65 which are secured to a plate or disk 65' and which radiate from the center thereof. This plate or disk has centrally connected thereto a shaft 66 which passes through a suitable opening in the base of the casing 32 as well as through openings in the upper and lower connecting arms 67 and 68 respectively provided upon a substantially U-shaped member 69 which is connected to the sides of the support 31. The shaft 66 has secured upon its free end a beveled tooth wheel 70 which meshes with a similar wheel 71 that is arranged upon a shaft 72. The shaft 72 is provided with a longitudinally arranged spline which engages in a suitable notch which communicates with the bore of

the toothed wheel 71 to permit of the said wheel sliding upon the said shaft. The beveled wheel 71 is retained in mesh with the wheel 70 by arranging the same adjacent 5 one of the arms of the U-shaped member 69, the shaft passing through suitable openings in the said arms of the said member 69. This shaft 72 has its ends journaled in suitable bearings 74—74 arranged upon the 10 deck 5 of the locomotive and the said shaft adjacent one of its bearings 74 is provided with a pulley wheel 75 which receives an endless belt 76, the said belt being trained over a pulley wheel 77 arranged upon the 15 shaft of the engine 78, which, in the present instance, being illustrated as the means for actuating the apparatus. The engine may be of any substantial but comparatively cheap non-reversible type as it is desired 20 that the shaft 72 rotate at all times in one direction, but any class of engine may of course be employed. The engine 78 receives its power through a pipe 79 which communicates with the boiler 4 of the locomotive and the engine moves the shaft 72 25 to rotate the rotor or feeder blades 65 in the direction of the arrow on Fig. 4 of the drawings.

The casing 32 is formed upon one of its 30 sides with a longitudinally extending spout 80, the same being preferably rectangular in cross section and being of a length to permit of the same being arranged adjacent the furnace door when the casing is moved to 35 communicate with the said doorway.

As previously set forth, it is one of the objects of the present invention to provide means whereby the fuel may be delivered to any desired part of the fire box, and at 40 any desired distance therein from the doorway of the fire box. To direct the fuel the spout 80 is provided with a pair of arcuate members or wings 81 and 82 respectively, the same being arranged to the opposite sides of the spout 80, the said members 81 and 82 45 being curved or rounded toward each other and the said members may be provided with upper and lower connecting plates if desired. Each of the wings adjacent its free 50 end and upon its opposite edges has pivotally connected thereto links 83 and 84 respectively, each pair of links are connected with each other and with the spout 80 by a pivot 85. The wings 81 and 82 at their rear 55 ends are also provided with angularly arranged arms or links 86 and 87 respectively, the said arms preferably crossing each other and being centrally pivoted to the upper 60 wall of the spout, as indicated by the numeral 88, while connected with the portions of the arms extending beyond the pivot are longitudinally arranged flexible operating members, such as chains 89 and 90. The numerals 91 and 92 indicate equalizing 65 springs which are secured to the rear ends

of the members 81 and 82, and which have their free ends secured, as at 93, to the upper and lower faces of the chute and to the rear of the pivot 88.

By reference to Fig. 7 of the drawings it 70 will be noted that when the flexible operating elements 89 and 90 are released, the equalizing springs 91 and 92 will swing the members 81 and 82 upon their pivots to permit of the said wings being moved to fully 75 unclose the outlet mouth of the spout 80, so that the fuel passing through the spout will be directed centrally of the fire box. Now, should a tension be exerted upon, say, the flexible member 89, and the second flexible 80 operating member 90 released, the member 81 will be swung to bring its end partially over the outlet mouth of the spout 80, and likewise the member 82 will be drawn away 85 from the mouth and against one of the sides 85 of the spout. Thus it will be noted that the fuel will contact with the curved member 81 and be directed to the right hand side of the fire box. Should the member 89 be released and a tension exerted upon the flexible 90 member 90, the position of the members 81 and 82 is thereby reversed; that is, the member 81 will be brought against the side of the spout 80 and the member 82 would have its curved end over the outlet mouth of the 95 spout, and thus the fuel will be directed to the left hand side of the fire box. As stated, the members 89 and 90 are preferably in the nature of chains, and suitable hooks (not shown) are provided to engage with certain 100 of the links of the said members so as to regulate the curvature or angle at which the fuel is to be directed into the fire box.

The wings may be folded against the sides 105 of the spout when the coal is to be delivered directly to the center of the fire box, and the casing 32 may be rotated or oscillated by the handle B which is arranged within the bearings a to approximately an angle of 90°, thus projecting the coal to any desired portion of the fire box except, perhaps, to the remote corners thereof, in which instance, the wings are brought into action.

Arranged at a suitable point within the 115 cab of the locomotive is an indicator 94, the same being shown in detail in Fig. 12 of the drawings, and includes a segmental plate. This plate 94' is provided with three 120 series of numerals arranged in proper spaced relation with each other, while imprinted upon the said plate, preferably to the left hand end thereof are the markings "Large", "Medium", "Fine", each indicating the grade of fuel in the bin of the tender, the marking "Medium" being central of the 125 "Fine" and "Large" markings. The numerals are provided to indicate the distance or the number of feet that the fuel is to be projected into the fire box.

95 designates a hand or pointer for the 130

indicator, the same being pivoted, as at 96, to the central and depending arm of the indicator and said pointer is provided with an angular extension 97. Pivotally secured to the angular extension 97 is a rod 98 which in turn is pivotally connected to the link members upon the arms of a ball governor 99.

The numeral 100 designates the governor shaft, and 101 a beveled tooth wheel keyed upon the said shaft. The wheel 101 meshes with a similar beveled gear 102 that is secured to the shaft 72 driven by the engine 78.

15 The engineer is, of course, acquainted with the quality of fuel in the bin, and in accordance with the distance to which the fuel is to be propelled he regulates the steam in the valve of the engine. It will thus be 20 noted that by gradually increasing or decreasing the amount of steam let into the engine the velocity of the second feeder or rotor 65 will be governed, and, of course, the distance to which the fuel will be projected. Of course, the governor may be hitched up to the engine in a different manner if desired and the particular arrangement of parts as just described is simply an 25 exemplification of one of a number of methods which may be employed for producing the desired results.

The shaft 66 has secured thereon between the arms 67 and 68 of the U-shaped member 69 a second beveled wheel 104 which 30 faces an opposite direction to that of the first mentioned beveled wheel 70, and this wheel 104 meshes with a similar wheel 105 provided upon a longitudinally extending shaft 106. The shaft has one of its ends 35 journaled in a bearing opening in an offset member 107 in the bearing 31 and has its opposite end extending through a bearing 108 in the standard 47. This shaft 106 has secured thereon a sprocket wheel 109, and 40 the end of the shaft 54 is provided with a like sprocket wheel 110, a sprocket chain 111 being trained around the wheels 109 and 110. The shaft 106 is necessarily adjustable in a 45 longitudinal direction, and, therefore, comprises two sections 112 and 113 respectively, the section 113 having its end adjacent the free end integrally formed with a sleeve 114, the same having its bore provided with a longitudinally extending groove 115 to receive a spline 116 upon the end of the shaft 50 section 112.

Extending longitudinally below the splined shaft 54 and journaled in suitable bearings provided in brackets at the ends of 55 the trough of the delivery chute is a threaded shaft D, the threads of said shaft engaging with the threads in the bearing of one of the arms of said bracket, and this shaft has secured thereon reversely disposed beveled wheels E and F respectively. The

shaft 106 has its member 112 provided with a beveled wheel g and the support 47 is provided with suitable brackets H forming bearings for a vertically disposed shaft I, the said shaft having its opposite ends provided with beveled wheels J and k respectively. The beveled wheels E and F are connected by a sleeve K, the bore of said sleeve being provided with a longitudinal opening to receive a spline in the non-threaded end of the member D.

The letter N designates a shifting or throwing lever connected to the sleeve K of the sprockets E and F, and as the shaft I is constantly in motion when the shaft 106 70 is revolved, it will be noted that by operating the shifting member N either of the sprocket wheels E or F may be brought into engagement with the sprocket wheel k thus revolving the shaft in either of two directions and as a consequence moving the elevator longitudinally of the conveyer toward either of its ends.

It will be noted that the top of the fuel deliverer or rotor casing is substantially 90 dome-shaped or flares downwardly to its body from its central coal receiving opening, and in order to rotate the said casing I provide the same at suitable points upon the top thereof with a pair of spaced alining bails a, 95 the said bails adapted to receive a removable handle B, the same being fully disclosed in the drawings.

The shaft 66 is preferably provided with an annular shoulder 66' that underlies the 100 bearing in the members 31 through which the said shaft passes and as a consequence serves as a support for the said members 31.

What is claimed is:—

1. In a mechanical stoker, the combination with a rotary feeder including a casing having an outlet spout and curved wings pivoted to the opposite sides of the spout, link members connected with the wings adjacent the outer end thereof and pivotally secured together and connected to the outlet spout, an arm pivotally connected with each of the wings adjacent the inner end thereof, said arms being arranged one over the other and pivotally connected, an operating element for each of the arms, and spring means connected with each of the wings to normally retain the wings against sides of the spout.

2. In a mechanical stoker, a horizontally 120 disposed rotary feed member, an endless conveyer delivering to the feed member, said conveyer having its outer end mounted on a pivoted support, an elevator including an endless chain connected with and longitudinally adjustable upon the conveyer, a carriage supporting the free end of the elevator, a rotary shovel for the elevator, and means for simultaneously operating all of 125 said members.

3. In a mechanical stoker, a horizontally disposed rotatable fuel feed member, means for operating the feed member, a laterally movable support for the feed member, a delivery conveyer pivotally connected with the support adjacent one end thereof and having its opposite end mounted upon a pivoted support, an elevator having one of its ends connected with the frame of the conveyer, means comprising mechanism between the elevator and conveyer for moving the elevator longitudinally of the conveyer, a carriage supporting the elevator, and means for simultaneously operating the feed member, the conveyer and the elevator.

4. The combination with a fire box having a laterally disposed track, of a support engaging said track, a casing having an outlet spout arranged upon the support, a rotatable fuel feed horizontally disposed within the casing and having a shaft passing through the casing and through the support to pivotally connect the casing with the support, an endless conveyer having the outer end of its frame mounted upon a pivoted support and the inner end of the frame pivotally connected with the first mentioned support, an elevator having one of its ends supported upon a carriage and its other end connected with the casing of the conveyer, means for longitudinally adjusting the elevator upon the conveyer, means for rotating the shaft of the fuel feed, and means comprising apparatus connected with the elevator and with the conveyer for simultaneously actuating said elevator and said conveyer when the fuel feed is actuated.

5. In a mechanical stoker, a laterally movable support, a casing having an open top and an outlet spout, a fuel feeder within the casing, a shaft for the fuel feeder passing through the casing and the support and pivotally connecting the casing to the support, an endless conveyer for the casing having its inner end pivotally connected with the support and its outer end supported upon a pivoted member, an elevator for delivering to the conveyer, a carriage supporting the outer end of the elevator, means connecting the inner end of the elevator to the frame of the conveyer, means for rotating the feeder shaft, means actuated by said shaft for operating the conveyer and the elevator, and means comprising mechanism also actuated by the said feeder shaft for moving the elevator longitudinally with respect to the conveyer.

6. In a mechanical stoker, a laterally movable support, a casing having an open top and an outlet spout disposed horizontally upon the support, a fuel feeder within the casing, a shaft for the fuel feeder passing through the casing and through the support and pivotally connecting the casing with

the support, an endless conveyer, a frame including side members for the conveyer, a pivotal connection between the conveyer and the support, a pivoted support for the outer end of the conveyer, an endless elevator delivering to the conveyer, a frame including side members for the elevator, a carriage supporting the outer end of the elevator, a bracket upon the inner end of the frame of the elevator, a member disposed longitudinally of the conveyer, a bracket movable upon the said member and pivotally connected with the bracket of the elevator, means for revolving the shaft of the fuel feeder, means including mechanism actuated by said shaft for simultaneously operating the endless conveyer and endless elevator, and means including mechanism also actuated by said shaft for longitudinally adjusting the elevator with respect to the conveyer.

7. In a mechanical stoker, a laterally movable support, a fuel feeder arranged horizontally upon the support, a shaft for the fuel feeder passing through the support, a longitudinally disposed trough having one of its ends arranged over the feeder, an endless conveyer in the trough, shafts for the conveyer at the ends thereof and journaled in bearings in the trough, a U-shaped yoke secured to the trough and pivotally connected with the support, a pivoted standard for the outer end of the trough, a longitudinally disposed shaft journaled in bearings to one side of the trough, a longitudinally arranged rod upon the other side of the track, a sleeve upon the rod, a yoke member arranged transversely of the trough and connected with the sleeve and having a bifurcated end provided with bearing openings for the mentioned longitudinal shaft, means including members upon the end of this shaft intermeshing with similar members upon the end of one of the conveyer shafts, a longitudinally extending threaded shaft mounted in bearings and engaging in a threaded opening in the yoke, an operating shaft journaled in bearings and gearing with the shaft of the fuel feed, a connection between this shaft and the mentioned longitudinal shaft, a gear connection between the operating shaft and the threaded shaft and disposed to revolve the said threaded shaft in either direction, means for actuating the feeder shaft, and an endless elevator having one of its ends supported upon a wheeled carriage and its other end pivotally secured to the mentioned yoke upon the longitudinal shaft of the conveyer trough and means between the said longitudinal shaft and the said elevator for actuating the elevator when the shaft is rotated.

8. In a mechanical stoker, the combination with feeder means and conveying means for the feeder means, of an endless elevator

adjustably connected with the conveying means, a wheeled carriage supporting the elevator, and a rotary shovel connected with the elevator and adapted to be actuated when the said elevator is in motion.

9. In a mechanical stoker, the combination with feeder means and conveying means for the feeder means, of an elevator adjustably connected with the feeder means and connected with the actuating means for the feeder means and conveyer means, a wheeled carriage supporting the free end of the elevator, a rotary shovel connected with the elevator and adapted to be actuated by the actuating means for the elevator, said shovel having a rim inclined in the direc-

tion of the elevator and having spaced buckets secured to the said rim, each of said buckets including a back plate secured to the rim and projecting thereabove, spaced 20 sides for the back plate, one connected with the outer edge of the rim and the other spaced from the inner edge of the rim, and a top plate connected with the said side and back plates.

25 In testimony whereof I affix my signature in presence of two witnesses.

WILLIAM S. HASLEU.
